C. R. FLEISCHMANN

PAPER HOLDER

Filed March 28, 1922

WITNESS.

O.E. Johnson.

INVENTOR
CHARLES R. FLEISCHMANN.
BY Chas. G. Gilman
ATTORNEY.

UNITED STATES PATENT OFFICE.

CHARLES R. FLEISCHMANN, OF CHICAGO, ILLINOIS.

PAPER HOLDER.

Application filed March 26, 1922. Serial No. 547,572.

To all whom it may concern:

Be it known that I, CHARLES R. FLEISCHMANN, a citizen of the United States, and residing at Chicago, in the county of Cook and State of Illinois, have invented certain new and useful Improvements in Paper Holders, of which the following is a specification.

This invention relates, generally, to improvements in paper-holders, but has particular relation to a type of such holders adapted for enclosing against exposure, a paper roll in such a way that the sheet or ribbon of paper comprising the roll can be readily dispensed and unwound therefrom through a suitable passage-way of the casing and torn off in pieces or strips of the desired lengths or sizes, and it consists in certain peculiarities of the construction, novel arrangement and combination of the parts thereof as will be hereinafter more fully set forth and specifically claimed.

The main object of the invention is, to provide a paper-holder of the above mentioned type or character, which shall be simple and inexpensive in construction, attractive in appearance, strong, durable, sanitary and efficient in operation and adapted for support on the wall of a room or other upright support, which, while it is more particularly intended for use in bath rooms and for holding rolls of paper, one at a time, to be used as shaving paper, yet it is applicable for use as a toilet-paper holder, or for holding a roll of paper for commercial purposes.

Another and important object of the invention is the provision of a paper holder of such construction that the roll of paper, as well as the sheet or ribbon extended therefrom in position to be dispensed or removed from the roll and torn off, will be protected from exposure or handling, thereby affording a sanitary holder.

Still another and important object is the provision of means for automatically clamping the sheet of paper as it is pulled from the roll or dispensed through the passage-way in the casing therefor in such a way that the paper may be torn off in strips or pieces of the desired size or lengths without danger of the sheet or ribbon "back lashing" or becoming disarranged on the roll.

Other objects and advantages will become

apparent from the following description and explanation.

In the accompanying drawing, which serves to illustrate an embodiment of the invention—

Figure 1 is a side view of the holder illustrating by dotted lines about the position 60 the door or cover of the holder will occupy when a roll of paper is being placed therein.

Fig. 2 is a front face view.

Fig. 3 is a transverse sectional view taken on line 3—3 of Fig. 2, looking in the direction indicated by the arrows.

Fig. 4 is a face view partly in section and partly in elevation with the door or cover of the casing removed, and illustrating part of the front wall of the casing broken away.

Like numerals of reference refer to corresponding parts throughout the different views of the drawing.

The reference numeral 5 designates the body or casing of the holder, which body is substantially rectangular in shape when viewed in plan and looking towards the face thereof but cross-sectionally has its upper portion forwardly and downwardly rounded and its lower portion somewhat horizontally elongated, as will be clearly seen in Figs. 1 and 3 of the drawing. This casing or body is by preference made of sheet metal and has the front portion of its bottom extended upwardly in a forwardly inclined plane as at 6, see Figs. 1 and 3 of the drawing. This up-turned portion 6 has extended forwardly and downwardly therefrom a resilient extension 7, which resilient portion is free from the sides 8 of the front part of the casing 5, while the upwardly inclined portion 6 of the floor of the casing is by preference secured to said side walls. The lower edge of the clamp or extension 7 terminates about flush with the lower edge of the front wall 9 of the casing, which front wall is provided with a vertically elongated opening 10 to register with a similar shaped opening 11 in the aforesaid clamp or extension 7, which normally lies in contact with the inner surface of the front wall 9 of the casing.

By this arrangement it is manifest that the upwardly extended portion 6 of the floor of the casing and the rear wall thereof, will provide a receptacle in which the paper roll 12 may turn when the sheet 13 or rib-

bon of paper is pulled or unwound therefrom.

The front wall 9 of the casing is provided near its upper edge with a pair of spaced horizontally elongated slots or openings 14 for the reception and operation of hooks 15 with which the lower edge of the cover 16 for the casing is equipped. This cover is provided at its rear edge with a depending catch 17 to overlap the rear wall of the casing 5 and to engage the same so as to hold the cover in its closed position, it being understood that the cover is of sufficient dimensions to close the space between the side walls and front and rear walls of the casing.

In Figs. 2 and 3 of the drawing, it will be seen and understood that the upper portion of the clamp or extension 7 is rearwardly deflected from the upper portion of the front wall, thus providing a space between said portions into which, the free end of the ribbon or sheet 13 of the paper roll can be readily inserted so that afterwards said sheet or ribbon may be extended downwardly between the contacting portion of the clamping extension 7 and the inner surface of the front wall of the casing. The operation of extending the ribbon or sheet downwardly between the member 7 and front wall 9, may be performed after the free edge of the sheet 13 is exposed through the openings 10 and 11 by placing the thumb of one hand on the outside of the front wall 9 and the front finger of said hand on the inner surface of the member 7, when it is manifest the free edge of the paper may be engaged between said thumb and finger and pulled downwardly until the lower portion of said openings are reached, thus causing the lower or free edge of the sheet 13 to depend below the bottom of the front wall, when said depending portion can be pulled downwardly until the desired length of paper is measured off, when it is evident the sheet may be turned against the lower edge of the front wall 9 and torn off.

Of course, the ribbon or sheet 13 can be placed between the clamping member 7 and front wall 9 of the casing by pressing the lower portion of the member 7 rearwardly and then inserting the free portion of the sheet through the space between the member 7 and front wall. It will be understood that after a piece of the paper has been torn off, the free or outer edge of the sheet or ribbon will lie in co-incidence with the lower edge of the front wall of the casing and will be difficult to reach at said point, but the openings 10 and 11 in the front wall and clamping extension 7, respectively, provide means for grasping the sheet of paper or ribbon between the thumb and fore-finger as above mentioned, and as the openings are elongated, it is manifest that the downward movement of the thumb and finger with the

sheet held between the same, will cause the lower portion of the sheet to be ejected from the casing and that portion thereof connected to the roll unwind therefrom.

The extension 6 rising from the floor of the casing and extending forwardly thereof, may or may not be fixed to the side walls of the casing. The upper portion of the rear wall of the casing is provided with a pair of horizontally elongated slots 18 to receive 75 nails or screws used for supporting the casing on a wall or upright.

By reference to Figs. 2 and 4 of the drawings, it will be seen and understood that the front wall 9 of the casing and the member 7 which co-operates with said wall, is each provided with an elliptical opening, which openings present their longitudinal axes vertically, and that these openings co-incide with one another and are unbroken. By 85 this arrangement it is manifest that only a restricted amount of the sheet 13 can be ejected from the bottom of the front end of the casing, without releasing the grip between the thumb and fore-finger on the sheet 90 of paper, as before explained. This arrangement will act to prevent unnecessary waste of the paper.

In practice I prefer to use a roll of paper the width of the sheet or ribbon of which is such that the edges thereof will closely approach or contact with the inner surfaces of the sides 8 of the casing, for the reason, when the sheet or ribbon 13 is extended slightly below the lower edge of the front wall of the casing, said extended portion may be manipulated against the lower edge of the front wall of the casing in such a way that the sheet will be severed thereby in a transverse line across the sheet, the contact 105 between the edges of the sheet with the walls 8 serving to keep the sheet of paper in alignment with said walls.

Having thus fully described my invention, what I claim as new and desire to 110 secure by Letters Patent is—

1. A paper holder consisting of a casing having an unbroken opening in its front wall and provided with a movable cover for its upper portion, the floor of said casing having an upwardly and forwardly inclined portion extended transversely between its side walls and spaced from its front wall and provided with a forwardly and downwardly disposed clamping extension to contact with said front wall to clamp a sheet of paper there-between, the said clamping extension having an unbroken opening co-inciding with said first named opening.

2. A paper holder consisting of a casing having a vertically elongated opening in its front wall and provided with a cover hinged at one of its edges to the upper portion of said front wall, the floor of said casing terminating at its front portion a distance rear- 130

- wardly of the lower edge of the front wall and having integrally therewith an upwardly and forwardly inclined partition extended transversely between the side walls 5 of the casing and spaced from its front wall, said extension having integrally therewith a forwardly and downwardly disposed clamping member to co-act with said front wall for clamping a sheet of paper there-between, 10 said clamping member having a vertically elongated opening co-inciding with said first named opening, at least one of said openings being unbroken.
- 15 3. A paper holder consisting of a casing having an elliptical opening disposed with its longitudinal axis vertically in its front wall and provided with a cover hinged at one of its edges to the upper portion of said front wall, the floor of said casing terminating at its front portion a distance rearwardly of the lower edge of the front wall and having integrally therewith an upwardly and forwardly inclined partition extended transversely between the side walls 20 of the casing and spaced from its front wall, 25 said extension having integrally therewith a forwardly and downwardly disposed clamping member to co-act with said front wall for clamping the sheet of paper there-between, said clamping member having an 30 elliptical opening in register with said first named opening.

CHARLES R. FLEISCHMANN.
